HEAT TREATING APPARATUS

Application filed January 28, 1931. Serial No. 511,262.

This invention relates to an apparatus for heat treating materials, and more particularly to an apparatus for calcining limestone and other alkaline earth carbonates.

- 5 The invention relates to the type of apparatus in which the material to be treated is passed in a thin pervious layer through a heating zone where gases heated to the calcining temperature are caused to pass down-
 10 wardly through the entire layer and provides for producing the hot gases and uniformly distributing them over the layer of material under treatment. This is accomplished by locating the burners in a portion of the heat-
 15 ing zone sufficiently remote from the material so that complete combustion is obtained before the hot gases are applied thereto. A plurality of burners are placed along the heating zone and are adapted to be individually controlled to permit regulation of the heat distribution longitudinally of the apparatus.

The invention further consists in the new and novel features of operation and the new 25 and original features of construction and combinations of parts hereinafter set forth and claimed.

Although the novel features which are believed to be characteristic of this invention 30 will be particularly pointed out in the claims appended hereto, the invention itself, as to its objects and advantages, and the manner in which it may be carried out, may be better understood by referring to the following description taken in connection with the accompanying drawings forming a part thereof, in which

Fig. 1 is a side elevation, partly in section, of a heat treating machine constructed in 40 accordance with the present invention;

Fig. 2 is a vertical section of the machine taken along the line 2—2 of Fig. 1;

Fig. 3 is a horizontal section through a portion of the heating chamber taken along the 45 line 3—3 of Fig. 2 showing the shape of the inlet ports; and

Fig. 4 is a half transverse section of a modified form of the device in which the burners are inserted from the bottom of the 50 heating chamber.

Like reference characters denote like parts in the several figures of the drawings.

In the following description and in the claims, various details will be identified by specific names for convenience, but they are 55 intended to be as generic in their application as the art will permit.

Referring to the drawings more in detail, the invention is shown as applied to a machine comprising a plurality of pallets 10 60 having perforate bottoms which are supported on a suitable trackway 11 and are driven by a driving wheel 12 which is adapted to engage said pallets and force the same along said trackway. Track 11 is supported on a 65 framework 13 which may be of any convenient construction and which also carries a wind-box 14 which communicates with the entire under surface of said pallets as they are passed along track 11 and forms a comparatively tight seal for preventing escape of gases. The gases may be withdrawn through pipe 15 which extends into the side of wind-box 14 and communicates with a suitable suction apparatus (not shown). A 70 damper 16 may be used to regulate the suction applied to the perforate bottoms of the pallets for drawing gases therethrough. Any dust that may drop into the wind box 75 may be removed through hinged cleanout doors 31.

For heat treating the material in said pallets, there is provided a heating chamber 17 formed by a roof 18, side walls 19 and bottom members 24 of refractory material. Said 80 chamber overhangs the sides of the pallets a substantial distance, and the bottom members 24 extend over the pallets sides to protect the same from the intense heat of the gases which are drawn downwardly through the 85 charge. A plurality of burners 21 communicate with fan shaped ports 20 in the side walls 19 and receive fuel, such as gas or oil, from a header 23. Each of said burners is provided with a valve 22 whereby individual 90 regulation of the burners may be obtained.

Said ports 20 are so located with respect to the pallets 10 that the hot gases are caused to travel a substantial distance before being applied to said pallets. This permits com- 100

place combustion to take place before the gases come in contact with the charge and also assists in maintaining an even distribution of gases over the entire charge. The overhanging portion of the heating chamber in which the burners are placed provides a separate combustion section in which the hot products of combustion are formed out of contact with the charge and complete combustion of the fuel is obtained before they are passed downwardly therethrough from the heating chamber.

The above described heating chamber is supported by a suitable framework 25. Flexible members 26, such as reenforced asbestos, may be secured to the underside of base members 24 in position to contact with the sides of the pallets for forming a substantially gas tight seal and preventing the escape of the hot gases.

A charge of material to be treated may be applied to the pallets by means of hopper 27 which is mounted directly above the pallets in such position that the pallets are caused to pass thereunder prior to their passage through heating chamber 17.

After the pallets have passed through the apparatus they are inverted and dump their charge into a suitable receiver (not shown), and thereafter pass down the inclined track 30 into engagement with driving wheel 12, thereby forming in effect a continuous chain of moving pallets.

In the operation of the above described apparatus the material, such as limestone, is applied in a thin permeable layer to the various pallets as they pass under hopper 27. This layer then passes through the heating chamber 17 containing gases heated to a calcining temperature, which are passed downwardly through the layer into wind-box 14 and suction pipe 15. The speed of travel of the pallets may be so regulated that the material is held in the heating chamber for a sufficient period of time to cause the calcining to proceed to the desired extent.

The provision of a separate combustion section, spaced from the charge, permits the gases to be completely burned and uniformly heated before they are applied to the bed of material in the heating chamber, and assists in obtaining a uniform transverse distribution of the hot gases.

The fan shaped ports permit the gases to spread out lengthwise of the heating chamber so that substantially the entire chamber is filled with the hot gases. The longitudinal distribution of the gases may be controlled by suitable regulation of valves 22. In certain instances, it may be desirable to maintain the entrance end of the heating chamber at a higher temperature than the discharge end, in order to partly offset the cooling tendency of the cold layer of incoming material. The regulation, however, may be controlled so

that the calcining proceeds uniformly and is complete when the pallets emerge from the discharge end of the heating chamber.

The details of the burners have not been completely set forth inasmuch as the burners are of standard construction and it is contemplated that oil burners or gas burners may be employed. Also the burners may be provided with suitable means for regulating the combustion therein, as for example, a suitable air control 33 as well as the fuel control valves disclosed.

In the form of the invention illustrated in Fig. 4, the construction of the machine is similar to that of the machine illustrated in Figs. 1-3 with the exception of the burners which are arranged to direct the flame upwardly through base 24, instead of horizontally through side walls 19. The parts accordingly have been given corresponding reference numerals and the construction may be understood by referring to the foregoing description. In Fig. 4 the gases of combustion impinge on the roof 18 and are directed by said roof downwardly onto the bed of material contained on the pallets. The curvature of the roof thus aids in directing and distributing the gases uniformly across the charge.

It will be seen that this invention provides a continuous heat treatment apparatus of the type in which hot gases are drawn through a layer of material to deliver heat thereto in which by use of a number of separately regulatable fuel burners, each projecting hot combustion gases over a comparatively small area of the layer, wide variation in the heat treatment is possible while maintaining uniform treatment as to the material as a whole. By suitable regulation of the individual burners, the heat treatment given the material at different points within the chamber may be maintained the same, or may be varied widely. For example, the burners may be adjusted to give an intense initial heating, followed by a prolonged lower temperature treatment, or annealing, or the material may be slowly warmed up and given a final brief high temperature treatment, and other variations will be understood by those skilled in the art. In any event, since the flow of material through the chamber is uniform, all portions of the material receive the same heat treatment.

While certain novel features of the invention have been disclosed and are pointed out in the annexed claims, it will be understood that various omissions, substitutions and changes may be made by those skilled in the art without departing from the spirit of the invention.

What is claimed is:

1. In an apparatus for heat treating material, a heating chamber in which a charge of said material is heated, a series of receptacles having perforate bottoms for supporting

said charge in a pervious layer, said receptacles being movable successively through said heating chamber, a portion of said heating chamber overhanging said receptacles, 5 and openings for burners in said overhanging portion, said burners being located a sufficient distance from said receptacles so that the combustible material is completely burned before being applied to said charge 10 and whereby a uniform transverse distribution of the hot gases is obtained.

2. In an apparatus for heat treating material, a heating chamber in which a charge of material is heated, a series of receptacles having perforate bottoms for supporting said material in a pervious layer, said receptacles being movable successively through said heating chamber, a portion of said heating chamber overhanging said receptacles and 15 openings for burners in said overhanging portion, said burners being spaced longitudinally of said chamber whereby the hot gases are applied throughout the length thereof.

25 3. In an apparatus for heat treating material, a heating chamber in which said material is heated, a series of receptacles having perforate bottoms for supporting said material in a pervious layer, said receptacles being movable successively through said heating chamber, a portion of said heating chamber overhanging said receptacles and 30 openings for burners in said overhanging portion, said burners being spaced longitudinally of said chamber whereby the hot gases are applied throughout the length thereof and said burner openings being fan shaped for spreading the gases longitudinally.

40 4. In an apparatus for heat treating material, a heating chamber in which a layer of said material is heated, a series of receptacles having perforate bottoms for supporting said material in a pervious layer, said 45 receptacles being movable successively through said heating chamber, a portion of said heating chamber overhanging said pallets and having transverse burner openings extending through the sides thereof, said 50 burners being located a sufficient distance from said receptacles so that the fuel is completely burned before the products of combustion are applied to said charge and whereby a uniform transverse distribution of gases 55 is obtained.

5. In an apparatus for heat treating material, a heating chamber in which a charge of said material is heated, a series of receptacles having perforate bottoms for supporting said material in a pervious layer, said receptacles being movable successively through said heating chamber, a portion of said heating chamber overhanging said pallets and having transverse burner openings extending 60 through the bottom thereof for introducing

ing combustible material into said chamber, said burners being located a sufficient distance from said receptacle so that the fuel is completely burned before the products of combustion are applied to said charge and whereby a uniform transverse distribution of gases is obtained. 70

6. In an apparatus for heat treating material, a heating chamber in which a charge of said material is heated, a series of receptacles having perforate bottoms for supporting said material in a pervious layer, said receptacles being movable successively through said heating chamber, portions of said heating chamber overhanging said pallets on 75 both sides and having burner openings extending therethrough for introducing combustible material into said chamber, said burners being located a sufficient distance from said receptacles so that the fuel is completely burned before the products of combustion are applied thereto and whereby a uniform transverse distribution of gases is obtained. 80

7. An apparatus for heat treating material comprising a heating chamber in which a charge of said material is heated, a series of receptacles having perforate bottoms for supporting said charge in a pervious layer, said receptacles being movable successively through said heating chamber, said heating chamber being of a substantial length whereby a plurality of said receptacles may be maintained therein and overhanging said receptacles transversely to provide a combustion section in which gases may be heated before they are applied to the charge, and burners located longitudinally of the heating chamber at spaced points and extending into said combustion section and spaced from the receptacles to permit the fuel to be completely burned out of contact with said charge whereby an even transverse distribution of the products of combustion is obtained. 90 95 100 105

8. An apparatus for heat treating material comprising a heating chamber in which a charge of said material is heated, a series of receptacles having perforate bottoms for supporting said material in a pervious layer, said receptacles being movable successively through said heating chamber, said heating chamber being of a substantial length whereby a plurality of said receptacles may be maintained therein and overhanging said receptacles transversely on both sides to provide 110 a combustion space out of contact with said charge, and having burners located longitudinally of the heating chamber at spaced points and extending into said combustion space 115 from opposite sides. 120 125

9. An apparatus for calcining limestone comprising a heating chamber in which a charge of limestone is heated, a series of receptacles having perforate bottoms for supporting said material in a pervious layer, said 130

receptacles being movable successively through said heating chamber, said heating chamber having base members of refractory material and a seal comprising flexible members carried by said base members and contacting with said receptacles to prevent escape of gases therebetween.

10. An apparatus for heat treating material comprising a heating chamber in which
10 said material is heated, a series of receptacles having perforate bottoms for supporting said material in a pervious layer, said receptacles being movable successively through said heating chamber, said heating chamber having
15 base members extending over the sides to protect them from the intense heat of the products of combustion, and a seal comprising flexible members of heat resistant material carried adjacent said base members and en-
20 gaging said receptacles to prevent leakage of hot gases.

In testimony whereof I have hereunto set
my hand.
